Charles J. Shepard of Brooklyn N.Y.
Letters Patent No. 975. Dated Jan 5th 1858.

The schedule referred to in these Letters Patent and making part of the same.

To all to whom these presents may come:

Be it known that I, Charles J. Shepard of Brooklyn in the county of Kings, and State of New York, have invented, made and produced a new and original design for the fronts and backs, tops and bottoms, of cast iron Cylindric .... Stoves, and I do declare that the following description and annexed drawing fully set forth and illustrate the same.

In the drawing, Fig. 1. is an elevation of a front half-plate of a cylindric .... cast iron stove, showing the ornaments on the same, and showing the top, e, and the bottom, d, in place. A like plate without the ash-fit opening, a, and with a pipe collar, f, forms the back half plate, on each of these half plates, a projecting ornamental flaunch, b, b, is shown forming the whole vertical line of division. This flaunch, b, b, serves and is used for the purpose of uniting the two half plates of the stove frequently together, with suitable screws and nuts, or if desired, the same may be cast together

In or near the center of the stove projects from the curve of the cylinder, a portion of the same, c, sufficient to enclose the ordinary cylindric .... fire brickz, or other nonconductor, such nonconductor serving to render the plates more durable when used.

Fig. 2. d, d, is plan of bottom plate and Fig. 3. e, e, is plan of top plate (and cover, g,) showing the ornaments thereon

Having thus set forth and shown the ornamental design of my cylindric .... stove, What I claim and desire to secure by Letters Patent is,

1st. The ornamentation and the ornamental design and configuration of the front and back plates.

2nd. The ornamental projection c, covering the fire brick, in or near the center of the front and back plates, it forming a projecting ring around the stove.

Des. 975

2

3^d. The ornamental flaunch, b.b. running vertically along the division of the front and back plates, it forming an ornamental finish.

4th. The ornamental design of the top and bottom plates.

All united to form an ornamental stove, as described and represented in the drawing.

In witness whereof I have hereunto set my signature

this 19th day of November 1857.
